UNITED STATES PATENT OFFICE.

ARTHUR CAMERON, OF CHICAGO, ILLINOIS, ASSIGNOR TO IVORY SAFETY RAZOR COMPANY, OF CHICAGO, ILLINOIS, A CORPORATION OF ILLINOIS.

DESIGN FOR A CHIME-WHISTLE.

42,832.

Specification for Design.

Patented July 30, 1912.

Application filed December 26, 1911. Serial No. 667,985. Term of patent 14 years.

To all whom it may concern:

Be it known that I, ARTHUR CAMERON, a citizen of the United States of America, residing at Chicago, in the county of Cook and State of Illinois, have invented a new, original, and ornamental Design for Chime-Whistles, of which the following is a specification, reference being had to the accompanying drawing, forming part thereof.

Figure 1 is a perspective of a chime whistle involving my new design, showing two sides thereof, and with the loose or

coupling end of the same in the foreground. Fig. 2 is a different perspective of the same chime whistle, showing the other two sides thereof, and with the free or outer end of the same in the foreground.

I claim:

The ornamental design for a chime whistle, as shown.

ARTHUR CAMERON.
